UNITED STATES PATENT OFFICE.

JOHN THOMAS FITZPATRICK, OF CORINTH, TEXAS.

DEVICE FOR LIFTING KETTLES FROM STOVES, &c.

SPECIFICATION forming part of Letters Patent No. 746,809, dated December 15, 1903.

Application filed September 28, 1903. Serial No. 174,886. (No model.)

To all whom it may concern:

Be it known that I, JOHN THOMAS FITZPATRICK, a citizen of the United States, residing at Corinth, in the county of Denton and State 5 of Texas, have invented certain new and useful Improvements in Devices for Lifting Kettles from Stoves, &c.; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

15 This invention relates to new and useful improvements in devices for automatically lifting kettles from stoves when the water evaporates, to the extent of lightening one end of the beam on which the kettle is pivoted sufficiently to allow the other end of the beam to be drawn down by a suitable weight, and means for throwing the kettle, carried by the pivotal beam, to one side of the stove after the beam is tilted.

20 The invention consists in various details of construction and in combinations and arrangements of parts, which will be hereinafter fully described and then specifically defined in the appended claims.

25 My invention is illustrated in the accompanying drawings, in which—

Figure 1 is a perspective view of my invention, and Fig. 2 is a central vertical section.

Reference now being had to the details of 30 the drawings by letter, A designates a hollow piping having a top B, with a hook C fixed thereto, which is adapted to be held by means of a pin or other suitable fastening device D, attached to the ceiling of a room or other 35 suitable place. Mounted within said tubing is a rod E, the upper end of which is secured to a strap F, which is attached at its upper end to the under side of the top B. Projecting from the tubular portion A, adjacent to 40 its lower end, are the arms K, which have angled ends K' downwardly disposed, and pivoted to the lower end of the rod E is a balancing-bar N, to one end of which is connected a hook M or other attachment to the

bail of a kettle, and to the other end of the 50 said balancing-bar N is connected a rod Q, upon which weights are held.

The operation of my device is as follows: When it is desired to suspend a kettle upon or over a stove, a quantity of water is placed 55 in the kettle and a weight equal to the amount of water which it is desired to have evaporate before the pot is raised from the stove is placed upon the rod Q. When the apparatus is adjusted for use, the bar N is substantially 60 in a horizontal position, and by giving a partially rotary turn to the rod E the strap F will be under tension and twisted. When it is desired to hold the kettle over the stove, the bar N is caught behind one of the angled ends 65 K' of the arms K and held over the stove. When the water in the kettle evaporates sufficiently to allow the bar N to tilt below the angled end engaging said bar, the rod E will be partially rotated under tension of said 70 strap sufficiently to throw the kettle to one side off the stove.

While I have shown a particular construction of apparatus illustrating my means for raising automatically a kettle from the stove, 75 it will be understood that I may make alterations in the detailed construction of the same without departing from the spirit of the invention.

Having thus fully described my invention, 80 what I claim as new, and desire to secure by Letters Patent, is—

1. An apparatus for lifting kettles from stoves comprising a tubing suspended from the ceiling or other fixed object, a rod mounted 85 within said tubing, a strap connecting the rod to the top of the tubing, said rod adapted to have a partially rotary movement within the tubing, a balancing-bar pivoted to the lower end of said rod, weights mounted upon one 90 end of said bar and a kettle attached to the other, and means for holding the rod under tension of said strap from rotating.

2. An apparatus for holding kettles over stoves comprising a tubing having a closed 95 top, a hook secured to the said top adapted for connection to the ceiling or other part of a room, a rod mounted within said tubing,

2
and a strap secured to the end of said tubing and to the inner end of said rod, a bar pivoted to the lower end of the rod, angled arms projecting from said tubing and adapted to engage said bar when inclined and hold the same under tension of said strap which is twisted as the rod is partially rotated, and a weight fastened to one end of said bar and the

other end adapted to hold a kettle, as set forth.

In testimony whereof I hereunto affix my signature in presence of two witnesses.

JOHN THOMAS FITZPATRICK.
